UNITED STATES PATENT OFFICE.

MELVILLE D. JONES, OF SOMERVILLE, MASSACHUSETTS.

LAWN-SPRINKLER.

SPECIFICATION forming part of Letters Patent No. 462,902, dated November 10, 1891.
Application filed December 12, 1890. Serial No. 374,485. (No model.)

To all whom it may concern:

Be it known that I, MELVILLE D. JONES, a citizen of the United States, residing at Somerville, in the county of Middlesex and State of Massachusetts, have invented certain new and useful Improvements in Lawn-Sprinklers; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to lawn-sprinklers; and my present improvement consists in the peculiar construction and arrangement of the liquid-distributing arms, whereby not only the speed of the revoluble portion of the sprinkler can be regulated, but the throw of the water can likewise be controlled, assuming that the head or pressure remains constant.

The drawings represent in Figure 1 a plan of a lawn-sprinkler embodying my improvements. Fig. 2 is a side elevation showing the arms arranged obliquely with respect to the plane of rotation. Fig. 3 is a vertical diametrical section of the revoluble head. Fig. 4 is a sectional elevation of the stationary spindle.

In said drawings, 2 represents a hollow pipe or support provided with a spindle portion 3, preferably tapered, which terminates in a screw-threaded portion. Upon the latter is placed an ornamental retaining-nut 4, preferably hollow and adapted to enable the revoluble head of the sprinkler to be removed or to be retained loosely in position when rotating. The head 5 of the sprinkler is shown as a short cylindrical tube formed with an upraised or projecting rib 6, to which are secured a series of liquid-distributing arms 7. These arms are supplied from the pipe 2 by means of the apertures 8 cut in the spindle 3, which is of a size to fit the bore of the head, and thus allow free rotation of the latter. Furthermore, the distributing arms 7, in which is embodied the gist of my invention, are composed of segmental or curved pieces of hollow tubing 9, made in short lengths, closed at both ends, and suitably punctured

or bored to create a series of small holes 10, from which the liquid-supply is discharged. Moreover, these segmental pieces are attached to or formed integral with hollow tubes 12, which unite them to the head 5. Preferably, such connecting-tubes are radially disposed, and their inner ends are screw-threaded to engage in the head to form a water-tight connection, while at the same time allowing the arms to swing from the horizontal to the vertical and permitting of changes in position with respect to the plane of rotation of the head. Thus it will be seen that each of the liquid-distributing arms may be swung through an arc of ninety degrees. Fig. 1—a plan—represents them in one and the same plane or all horizontal, while in Fig. 2 they are set at about thirty degrees therefrom. By such construction, and owing to the form of the segmental pieces, the speed of the revoluble head can be readily controlled. Thus when all the arms are in the same horizontal plane, the head is stationary and the sprinkler acts as a fountain with a fine spray. As the said segmental pieces or arms collectively form nearly or quite a complete circle, as shown in Fig. 1, they distribute the water in all radial directions from the center of the sprinkler, whether the head be in revolution or not. When the arms are set at forty-five degrees, the water is distributed the greatest distance, while if they are set in a vertical position the rotation is at a maximum, and the spray is not delivered so far. To secure the best results the delivery-holes 10 are bored at right angles or normally to the surface of the arms at these special places.

In the drawings all the segmental pieces are arranged at the same distance and concentrically about the revoluble head. However, the connecting-tubes may vary in length and still allow said segmental pieces to produce the same general results.

What I claim is—

1. A lawn-sprinkler composed of a stationary portion for a water-supply and a revoluble head provided with segmental arms, capable of axial movement in a plane at angles to the plane in which the head is said arms collectively forming a nearly complete circle, substantially as specified.

2. The combination, with the fixed

and its spindle 3, provided with openings or apertures 8 and the removable nut 4, of the tubular revoluble head 5, having an enlarged or projecting portion 6, provided with radial openings, and segmental arms 7, which collectively form nearly a complete circle, and the tubes 12, carrying said arms and loosely entering said radial openings, and thus adapted to be turned to cause the said arms to assume different positions, substantially as set forth.

3. The combination, with the fixed tubular support and its apertured spindle, of a hollow revoluble head, a series of perforated segmental arms closed at both ends and concentric with said head, said arms collectively forming nearly a complete circle, and connecting-tubes loosely entering said head, whereby the arms may be held coincident with or obliquely to the circular path described by the head, substantially as explained and stated.

4. In a lawn-sprinkler, the combination, with a fixed tubular portion for a water-supply, of a hollow revoluble head having a plurality of perforated arms adjustably connected therewith and thus adapted to be turned in a plane at right angles to that in which the said head rotates, said arms being arranged about said head at all sides thereof, and being thus adapted to throw the water in all directions radial to said head, whether the latter be in revolution or not, substantially as set forth.

In testimony whereof I affix my signature in presence of two witnesses.

MELVILLE D. JONES.
